MOUNT FOR INCANDESCENT-LAMP FILAMENTS.

Application filed May 26, 1920. Serial No. 384,279.

This invention relates to types of mounts for the filaments of electric incandescent lamps, particularly those in which the filaments are operated at very high temperatures, as in incandescent lamps that are utilized as light sources in projection apparatus or systems.

In the present form of construction embodied in incandescent lamps used for projection purposes, it is customary to rigidly support the filament at a plurality of points, such as where the pitch of the coiled sections comprising the filament has been made relatively coarse, as, for example, between the closely wound sections and the terminals.

Inasmuch as the operating temperature of the filament of a lamp of this type is very high, there is a considerable elongation of the coiled sections for which compensation must be provided in order to prevent the several sections from warping or buckling out of their plane of mounting and thus seriously impairing the uniformity of the light derived from the lamp, as usually manifested by light and dark spots upon a screen. This displacement of the filament may be in several directions and of a rotary nature.

It is an object of this invention to overcome the above difficulty by the provision of a filament mount or support that will permit the segments comprising the filament to naturally expand and contract by reason of forces of thermal or other origin acting thereupon.

Another object of the invention is to provide a form of filament support which will permit freedom of expansion of the segments comprising the filament and direct or control this expansion along the lines of gravity.

Another object of the invention is to so mount the filament that the lines of force acting thereupon shall be in a given direction and substantially in a single plane.

A still further object of the invention is the provision of a filament mount or support that will confine the movement of the filament to a selected direction or plane but will permit freedom of motion in the desired or selected direction.

Other objects of the invention have to do with various features of construction and arrangement of parts which will hereinafter

be more fully described and set forth in the appended claims.

The means contemplated by us for practicing the invention comprise attaching the filament, by securing the terminal portions thereof, to the leading-in conductors and providing a frame structure carried by the conductors and so designed that the several segments of the filament shall be permitted to move in a rectilinear path, and, if desired, be restrained for rotating. Specifically, this may consist in supporting the filament pendant fashion and providing guide members adapted to cooperate with movable links connecting the filament therewith. These connecting links may be firmly secured to the filament and to each other in such a manner as to prevent the rotation of the several sections constituting the filament.

In the accompanying drawings, Fig. 1 is an elevation of a filament supported in a pendant position and provided with means for permitting the elongation and contraction thereof in a rectilinear path coincident with the force of gravity; Fig. 2 is a like view of a modification of the mounting shown in Fig. 1; Fig. 3 is an elevation of a filament so mounted that all motions, of whatever nature, excepting those in a rectilinear direction, are restrained; Fig. 4 is a similar view of a modified form of the construction shown in Fig. 3, and Fig. 5 is an elevation of a form of mounting coming within the invention and in which the expansion of the filament is in an upward direction with respect to the base of the lamp.

Throughout the several views of the drawings, similar reference characters refer to like parts.

A more detailed understanding of the invention may be had by reference to Fig. 1 of the drawings, in which relatively heavy nickle leading-in conductors 1 are sealed in a glass stem 2 and terminate in inwardly curved portions 3, the ends of which are oppositely disposed. Constituting a part of the stem 2, and juxtaposed relative to the leading-in conductors 1, is a glass arbor 4, the end of which is enlarged to provide means for inserting, in a vertical position, helical guide members 5. An overhead cross piece 6, preferably spot welded

to the leading-in conductors 1 but electrically insulated therefrom by glass insulators or beads 7, has downwardly extending therefrom a supporting link 8 which is adapted 5 to engage one of the coarse turns separating the several segments of the helical or coiled filament 9. The filament 9 is usually composed of a plurality of spaced and closely wound coils, each capable of forming a band 10 of light and disposed in parallel relation to each other in such a manner as to occupy substantially the same plane. The spaces intermediate the several coils are substantially equal in width to the diameter of the 15 coils.

The filament 9 is provided with terminals 11 which are secured to the ends of the curved portions 3 of the leading-in conductors. The terminals 11 are preferably 20 made of sufficient length to prevent the temperature of the coiled sections adjacent thereto from being materially different from that of the intervening sections because of the heat being more rapidly conducted away 25 by the leading-in conductors.

Connecting links 12 are attached to the lower coarse turns of the filament 9 and are adapted to reciprocate in the guide members 5. The links 12 are of sufficient rigidity 30 and length to afford a means for partially supporting the filament 9 and, at the same time, permit it to freely expand and contract under forces created by the temperature changes to which the filament and its 35 mount are subjected in the use of the lamp containing the same. In this form of construction, the movement of the filament is restrained to a rectilinear path corresponding in direction to the force of gravity.

The modification shown in Fig. 2 is similar 40 to the style of mounting shown in Fig. 1, the difference residing in the specific method of supporting the filament 9 and in the form of guide members 5 which are provided for accommodating the links 12. In this construction, each of the guide members 5 comprises a pair of anchors, one end of each of which is inserted in a glass or lava block 13 supported from the side of the corresponding leading-in conductor 1, while, its other end is provided with an eyelet adapted 45 to receive the corresponding connecting link 12. The eyelets of the respective pairs of anchors constituting the guide members are 55 in alignment with the links 12.

In Fig. 3 the suspension of the filament is somewhat different from that disclosed in Figs. 1 and 2, but is also of the pendant type. In this construction, the guide members 60 5 comprise oppositely disposed lava blocks 13 supported from the sides of the leading-in conductors. The lava blocks 13 are pierced longitudinally to permit the passage therethrough of the connecting links 65 12. The lower ends of the links 12 are bent

at right angles toward each other and are inserted into a lava bridge piece 14. Inasmuch as the top ends of the connecting links 12 are rigidly fastened to the filament 9, which is also true of the connecting link 70 8, the coiled sections, although permitted to move in a rectilinear path, are prevented from rotating by virtue of the links 8 and 12.

In the modification shown in Fig. 4, which is similar to the mounting illustrated in Fig. 75 3, the bridge piece 6 is dispensed with and the filament 9 is supported by having the terminals thereof bent at right angles to the coiled sections and welded to the leading-in conductors 1. The intervening segments are supported, at the top, by a hook 80 15, one end of which may be inserted in a glass pedestal 16 comprising a part of the stem 2 and the other end thereof attached to the coarse turn joining the central coiled 85 sections.

The connecting links 12 extend through a single pierced lava block 17 that is supported from one of the leading-in conductors. One end of each of the connecting links is fixed to the filament while the other end is provided with convolutions 18 adjacent to its connection to the pedestal 16. The function of the convolutions 18 is to 90 provide resilient means for allowing the filament to expand and contract.

In Fig. 5 the mounting is of the type 95 which may be termed an "overhead" construction, which is characterized by the filament being supported above the ends of the leading-in conductors. The terminal portions of the filament are secured to the ends of the leading-in conductors 1, and a bridge member of non-conducting material, such as 100 a lava block 20, carried by a suitable support, is secured to the conductors. The lava block 20 is drilled to receive the connecting links 12 which are similar, in construction and function, to the corresponding links 105 shown in Fig. 3. In the present modification, one end of the supporting link 8 is inserted into the glass pedestal 16 and its 110 other end is secured to the filament 9.

From the above description, it will be apparent that, in the various mountings 115 described, the filament is free to expand and contract in a rectilinear path, thereby greatly lessening the tendency of the filament to warp or twist out of its normal plane. This restraint may be further exercised by providing means, such as shown, for arresting any rotary movement of the filament, with the result that a more uniform light source 120 may be obtained from the lamp embodying 125 the filament.

While this invention has been set forth in certain preferred embodiments, it will be understood that modifications may be made without departure from the spirit and scope 130 thereof.

What is claimed is:

1. In an incandescent electric lamp mount, a coiled filament supported therefrom in a pendent position, said filament being composed of several sections, and means for restricting all the motions of said filament caused by temperature changes excepting those movements which may take place in a predetermined path said means including 10 guide members and links, the latter being connected to said filament, said guide members being connected with said links in a manner to permit substantially only reciprocating motion of said links within said 15 guide members, the former being fixedly secured to the movable portion of said filament and to each other in a manner to prevent oscillatory movement of the sections of said filament.
2. A filament mount of the pendant type comprising a frame having upright supporting members originating in a glass stem and connected by an overhead cross-piece, said supporting members terminating in inwardly curved portions oppositely disposed, a glass support juxtaposed relative to said supporting members, upwardly extending tubular guide members secured to said glass support, a filament consisting of several closely coiled sections separated by portions of relatively coarse pitch and provided with straight terminal portions, said terminal portions being attached to the curved portions of the filament supporting members, a link carried by said cross-piece for supporting the segments intermediate the terminal segments, and connected links adapted to reciprocate within said guide members and restrain in a rectilinear path 40 the movement of the several filament sections due to expansion and contraction.
3. A mount for an incandescent electric lamp comprising a stem, supporting members extending in approximately an axial direction therefrom, a filament consisting of a plurality of coiled sections, separated by a

relatively straight portion, disposed substantially parallel and provided with terminal portions connected to the supporting members, a tubular guide member supported by means of the stem and a link connected to an intermediate portion of the filament, for restraining distortion thereof and adapted to reciprocate in the guide member. 50

4. An incandescent electric lamp mount, comprising a coiled filament supported therefrom in a pendent position, said filament being composed of several sections, link members connected at their normal upper ends to said filament and at their lower ends to each other, guide members operating in conjunction with the connected links to confine the movement of said sections to a predetermined path. 55

5. An incandescent electric lamp mount, comprising a coiled filament supported therefrom in a pendent position, said filament being composed of several sections, link members connected at their normal upper ends to said filament, a non-conductive coupling 60 for uniting the lower ends of said links and guide members operating in conjunction with the connected links to confine the movement of said filament sections to a predetermined path. 65

6. An incandescent lamp mount, comprising a coiled filament supported therefrom in a pendent position, said filament being composed of several sections, link members connected at their normal upper ends to said filament, a non-conductive coupling 70 uniting the lower ends of said links, guide members disposed substantially intermediate the filament and said coupling and operating in conjunction with the links to confine the movement of said sections of filament to a predetermined path. 75

In testimony whereof, we have hereunto subscribed our names this twenty-first day of May, 1920.

ERTLE L. HARRINGTON.
